[57] CLAIM

The ornamental design for the auxiliary bicycle seat, as
shown and described.

DESCRIPTION

FIG. 1 is a left side elevational view of an auxiliary
bicycle seat showing my new design, it being under-
stood that the broken lines are for illustrative purposes
only;

FIG. 2 is a rear elevational view thereof;

FIG. 3 is a top plan view thereof;

FIG. 4 is a front elevational view thereof;

FIG. 5 is a right side elevational view thereof; and

FIG. 6 is a bottom plan view thereof.
